VACUUM TUBE

Radford P. Leonard, Santa Barbara, Calif., assignor to
Penta Laboratories, Inc., Santa Barbara, Calif.

Filed Mar. 8, 1963, Ser. No. 73,887

Term of patent 14 years

(Cl. D26—8)

Fig. 2.

Fig. 1.

Fig. 3.

FIG. 1 is a side elevational view of a vacuum tube, showing my new design, the appearance being the same from all sides;

FIG. 2 is a top plan view; and

FIG. 3 is a bottom plan view thereof.

I claim:

The ornamental design for a vacuum tube, as shown and described.
